DEMOUNTABLE COUPLING

Harry H. Merwin, Rutherford, N. J., assignor to
Western Electric Company, Incorporated, New
York, N. Y., a corporation of New York

Application January 30, 1937, Serial No. 123,214

1 Claim. (Cl. 287—129)

This invention relates to demountable couplings, and more particularly to such couplings for joining machine elements.

The invention has been found particularly useful in mounting flyer units in the frames of strand twisting machines of the general type disclosed in the H. H. C. Grondahl Patent No. 1,263,405 of April 23, 1918. It is desirable in such machines, as well as those in which the twisted strand is taken up on a flyer unit, that the unit be readily coupled to or uncoupled from its driving shaft and removed from the machine without requiring motion of the shaft and without disturbing adjacent mechanism of the machine.

An object of this invention is to provide a simple, practical and efficient demountable coupling for coupling and uncoupling machine elements.

In accordance with the above object, the invention in one embodiment thereof, as applied to a machine of the aforementioned type, contemplates a demountable coupling in which adjacent ends of the flyer unit and its driving shaft terminate in heads having diametral grooves in their opposed faces. Between the grooved faces of the heads are a plurality of abutting plates having radially extending keys projecting from their exterior faces which slidably fit the grooves of the heads on the flyer and its driving shaft, each set of cooperating grooves and keys being angularly disposed. The heads and plates are axially bored for the passage of strand and after assembly the plates are interbolted.

Other objects and advantages of this invention will more fully appear from the following detailed description, taken in connection with the accompanying drawing, wherein

Fig. 1 is an elevational view of a demountable coupling embodying the features of the invention shown applied to a flyer of a strand twisting machine, the flyer being shown diagrammatically;

Fig. 2 is an enlarged plan section of the coupling taken on the line 2—2 of Fig. 1, and

Fig. 3 is a vertical section taken on the line 3—3 of Fig. 2.

In the drawing the invention is shown as applied to a strand twisting machine, such as is used in the manufacture of telephone cable. Since the twisting machine is of a well known type, such as is disclosed in the aforementioned patent, as well as those machines in which the twisted strand is taken up on a flyer unit, and forms no part of this invention, the machine has been illustrated diagrammatically, since the details thereof are not necessary to a full under-

standing of the present application of the invention. Referring to the drawing, a flyer unit is indicated diagrammatically in broken outline at 10 (Fig. 1). At its upper and lower ends the flyer unit terminates in spindles 11 and 12, respectively, the upper spindle 11 being coupled to a driving shaft 13 journaled in a bearing fragmentarily indicated at 14 and the lower spindle 12 is journaled in a split bearing 15.

In order that the flyer unit 10 may be readily mounted on or removed from the twisting machine for replacement or repairs without dismantling or disturbing adjacent mechanism of the machine a demountable coupling indicated generally by the numeral 16 is provided whereby the upper spindle 11 of the flyer unit may be coupled or uncoupled from the driving shaft 13 without any motion of the shaft, particularly in a longitudinal direction. Similarly, the flyer unit 10 may be freed at its lower end from the split bearing 15 by detaching a removable section 17 of the bearing in a well known manner. No longitudinal motion of the flyer unit is necessary while coupling or uncoupling it to the driving shaft 13.

The demountable coupling 16 comprises a pair of shouldered collars or heads 18 and 19 which are keyed or otherwise suitably fixed to the driving shaft 13 and the upper spindle 11 of the flyer unit 10, respectively. The opposed larger outer faces of the heads 18 and 19 are predeterminedly spaced from each other in axial alignment and each has formed therein diametral grooves or key slots 20 and 21, respectively. Fitted in the space between and abutting the opposed outer faces of the heads 18 and 19 are a pair of annular abutting plates 24 and 25 each having integral with its outer face a pair of diametral lugs or keys 26 and 27, respectively. The keys 26 and 27 are so arranged on the plates 24 and 25, respectively, and of such dimensions that they closely fit in the slots 20 and 21 of the heads 18 and 19, respectively, so that each head and its associated plate comprising a set may be locked together for rotary motion. The fit of the keys 26 and 27 in the slots 20 and 21, respectively, is such that each of the plates 24 and 25 may be freely slid laterally into operative position, the keys 27 of the plate 25 being first aligned with the slots 21 of the head 19 and then slid into locking engagement. Thereafter, the plate 24 with the keys 26 thereof aligned with the slots 20 of the head 18 may be slid laterally on the plate 25 into operative position, the keys 26 being entered in the slots 20.

The plates 24 and 25 are larger in diameter than the larger portions of the heads 18 and 19 and are connected together by a plurality of bolts 28. Before the head and plate sets are connected together by the bolts 28 to complete the coupling operation, in order that the head and plate sets fixed respectively to the driving shaft 13 and the upper spindle 11 of the flyer unit 10 may be rotated as a unit, one set is rotated relative to the other set to position the slots and keys thereof at right angles to the slots and keys of the other set whereby the cooperating slots and keys are equally spaced about the axis of rotation of the driving shaft 13 and the flyer unit 10. The right angular disposition of the slots and keys of the head and plate sets when assembled, it will be noted, serves to lock the bolted plates 24 and 25 individually or as a unit from movement relative to the heads 18 and 19 until the bolts 28 are removed. In the particular application of the invention to a strand twisting machine the head 18 and its driving shaft 13 together with the upper spindle 11 of the flyer unit 10 and the plates 24 and 25 are all axially bored, as indicated at 30, 31 and 32, respectively (Figs. 1 and 3), for the passage of strand (not shown) to the flyer unit 10 in the operation of the machine.

When it is desired to disconnect and remove the flyer unit 10 from the twisting machine, it is merely necessary to disconnect the plates 24 and 25 from each other by removing the bolts 28 whereupon the abutting plates may be freely slid from locking engagement with the heads 18 and 19, thus disconnecting the driving shaft 13 from the upper spindle 11 of the flyer unit. To completely free the flyer unit for removal from the machine the removable section 17 of the split bearing 15 for the lower spindle 11 is removed. The flyer unit 10 thus uncoupled from the machine may be removed therefrom without requiring longitudinal motion of the driving shaft 13, the unit, or the spindles 11 and 12.

From the above description of the improved demountable coupling and one application thereof, it will be seen that a simple, practical, and efficient demountable coupling for machine ele-

ments is provided whereby a machine element may be readily mounted in operative position, or removed for replacement or repairs from a machine without requiring motion of the elements to which it is connected, and without longitudinal movement of the element being mounted on, or removed from the machine. 5

Although the invention herein described and illustrated is particularly well adapted for use in strand twisting machines, it will be understood that the invention is capable of other embodiments and many applications and is to be limited only by the scope of the appended claim.

In the preferred form of the invention shown, each of the annular plates 24 and 25 is transversely split into two parts along the plane 33 or 34 respectively, which renders it possible to disconnect the flyer unit from the driving shaft by removing the plates 24 and 25 or either of them even when the flyer is threaded with 20 strands, without first removing or cutting the strand. This is a desirable and useful feature in an apparatus comprising several flyers where it may be desired at times to have one of the flyers stationary while an associated flyer is rotating. 25 However, where this feature is not essential, each of the annular plates 24 and 25 may be made integral throughout.

What is claimed is:

In a demountable coupling for joining machine elements, heads connected to adjacent ends of axially bored coaxial machine elements, said heads having aligned spaced outer end faces with diametral keyways therein, a pair of transversely split plates of larger diameter than the 35 heads between the spaced faces thereof having diametral keys extending from their outer faces cooperating with the keyways of said heads for coupling each plate to its associated head, said plate keys arranged for slidably engaging or disengaging the keyways of said heads solely upon lateral movement of said plates, and means disposed outside the circumference of the heads for connecting the plates and thereby joining the machine elements. 40
